BOAT HULL

Peter A. Milne, South Benfleet, Essex, England, assignor
to Richmond Marine Limited, London, England

Filed June 26, 1969, Ser. No. 17,903

Claims priority, application Great Britain Dec. 30, 1968

Term of patent 14 years

Int. Cl. D12—06

U.S. Cl. D71—1

FIG.5

FIG.6

FIG.7

FIG.8

FIG.9

FIG. 1 is a perspective view from above of a boat hull embodying my new design;

FIG. 2 is a lower plan view thereof;

FIG. 3 is a side view thereof;

FIG. 4 is an upper plan view thereof;

FIG. 5 is a front end view;

FIG. 6 is a rear end view;

FIG. 7 is a cross-sectional view thereof on the line 7-7 of FIG. 3;

FIG. 8 is a cross-sectional view thereof on the line 8-8 of FIG. 3; and

FIG. 9 is a cross-sectional view thereof on the line 9-9 of FIG. 3.

I claim:

The ornamental design for a boat hull, substantially as shown.
